DESIGN FOR A BATHING SUIT

Tina Leser, New York, N. Y.

Application February 15, 1944, Serial No. 112,584

Term of patent 3½ years

(Cl. D3—17)

To all whom it may concern:

Be it known that I, Tina Leser, a citizen of the United States, residing in New York city, in the county of New York and State of New York, have invented a new, original, and ornamental Design for a Bathing Suit, of which the following is a specification, reference being had to the accompanying drawing, forming part thereof.

Fig. 1 is a front view of a bathing suit showing my design,

Fig. 2 is the rear view of the bathing suit shown in Fig. 1, and

Fig. 3 is a fragmentary view of the bathing suit shown in Fig. 1 with the edge portion thereof in loosened position, and the halter member thereof in closed position.

I claim:

The ornamental design for a bathing suit, substantially as shown.

TINA LESER.
